UNITED STATES PATENT OFFICE.

PAUL H. WHITE, OF INDIANAPOLIS, INDIANA, ASSIGNOR TO WHITE STEAM WAGON COMPANY, OF INDIANAPOLIS, INDIANA, A CORPORATION OF INDIANA.

STEAM-GENERATOR.

SPECIFICATION forming part of Letters Patent No. 707,996, dated August 26, 1902.

Original application filed May 27, 1901, Serial No. 62,038. Divided and this application filed September 7, 1901. Serial No. 74,683. (No model.)

To all whom it may concern:

Be it known that I, PAUL H. WHITE, a citizen of the United States, residing at Indianapolis, in the county of Marion and State of 5 Indiana, have invented a new and useful Steam-Generator, of which the following is a specification.

My invention relates to an improvement in steam-generators in which it is desired to produce steam rapidly and at high pressure.

The present application is a division of my application, Serial No. 62,038, filed May 27, 1901, and relates to the peculiar arrangement and construction of the furnace.

15 The generator has been especially designed for use in connection with automobiles, although of course it is not necessarily limited to such use. In generators designed for this use the steam consumption varies greatly, and 20 it is requisite that the furnace be of such character as to enable the production of a rapid and intense fire. Great difficulty has been encountered heretofore, however, in the use of other than liquid fuels in steam-generators for this purpose, for the reason that 25 if a fire of sufficient intensity be provided to maintain steam at the proper pressure while the engine is being operated the pressure rises very rapidly and the generator "blows off" 30 steam almost immediately upon shutting off steam from the engine. So far as I know no construction has heretofore been provided by which the heat from the furnace may be deflected from the generator, so as to prevent 35 the circulation of heat about or through the main body of the generator, but at the same time keep the generator at such temperature as to maintain the steam-pressure.

The object of my invention is to construct 40 a furnace capable of a long maintenance of a fire and to provide means for preventing the circulation of heat from the fire between the water-tubes or about or through the main body of the generator and to provide for a 45 supplemental outlet sufficient to keep the fire and to maintain pressure in the generator.

The accompanying drawings illustrate my invention.

Figure 1 is a side elevation, a portion of the 50 surrounding casing of the generator having

been removed. Fig. 2 is a section on line 2 2 of Fig. 1.

In the drawings, 3 indicates the tubes of a water-tube generator, which tubes are surrounded by a suitable casing 4, from the upper part of which leads a main flue or outlet 5. Mounted below the generator at the lower end of the casing 4 is any suitable form of grate, preferably that which forms the subject-matter of my pending application, Serial 60 No. 74,682.

Leading from the combustion-chamber 6 is a supplemental flue or outlet 7, which leads from a point below the main body of the generator upward to the flue 5, said supplemental flue being preferably lined, both inside and out, with an insulator, such as sheet-asbestos 9. At the point where the supplemental flue 7 joins the main flue 5 I mount a damper 10, which damper may be thrown so 70 as to close either the flue 7 or the flue 5. When the damper 10 is thrown so as to close flue 7, all of the heat from the furnace passes upward between the water-tubes or through the body of the generator and out through the 75 flue 5. If the damper 10 be thrown so as to close flue 5, however, a sufficient draft is maintained through flue 7 to maintain a fire; but at the same time the circulation of heat through the body of the generator is pre- 80 vented, sufficient heat being, nevertheless, maintained about the body of the generator to maintain or practically maintain the steam-pressure. It will be noticed that the supplemental flue when open leads the heated gases 85 away from the body of the generator, so that as soon as the said flue is opened and the main flue closed the action is substantially equal to a sudden drawing of the fire, yet there is sufficient heat maintained in the 90 body of the generator to keep up the steam-pressure. The supplemental flue makes it possible to maintain the fuel in good burning condition without an excess of heat in the generator, so that when the consumption of 95 steam is again resumed the fire is in proper condition to produce an adequate supply of steam.

Although I have shown my invention as applied to a water-tube generator, the arrange- 100

ment is equally applicable to any type of steam-generator.

I claim as my invention—

1. In a steam-generator, the combination with a furnace, of a main outlet leading therefrom above the body of the generator, a supplemental outlet leading from the furnace below the body of the generator, and means for controlling the passage of heat through the outlets so that when the main outlet is closed a non-circulating heat will be maintained in the body of the generator.
2. In a steam-generator, the combination with the main body of the generator, of a furnace, an outlet leading through the main body of the generator, a supplemental outlet passing around the main body of the generator, and means arranged above the main

body of the generator for controlling the passage of heat through said outlets.

3. In a steam-generator, the combination with the water-tubes thereof, of an inclosing casing, a furnace mounted beneath said tubes, a main outlet leading from said casing, a supplemental outlet passing around the water-tubes and communicating with the furnace below the water-tubes and with the main outlet above the water-tubes, and a damper arranged above the water-tubes so as to close either the supplemental outlet or the main outlet.

PAUL H. WHITE.
